HINGE STRUCTURE

Walter K. Nelson, Pittsburgh, Pa., assignor to
 National Casket Company, Boston, Mass., a
 corporation of New York

Application July 12, 1935, Serial No. 30,993

2 Claims. (Cl. 16—128)

This invention relates to new and useful improvements in hinge structures, and it is among the objects thereof to provide a hinged joint especially adapted for use on burial receptacles although the form of hinge may be employed generally and especially to replace the common form of so-called piano hinge.

The description of the invention will be in connection with its application to burial receptacles as an illustrative embodiment only, it being understood that I do not desire to limit my invention thereto.

The invention will become more apparent in connection with a description of the accompanying drawing constituting a part hereof in which like reference characters designate like parts and in which:

Fig. 1 is a front elevational view of a burial receptacle having a front drop so-called which is a hinged element embodying the principles of this invention;

Fig. 2 a view in perspective of a portion of the rear of the drop illustrating the hinge member;

Fig. 3 a front elevation of the casket greatly reduced and constricted illustrating the open or dropped position of the casket front wall;

Fig. 4 a plan view of a portion of the hinge as applied to a hinged joint;

Fig. 5 a transverse section of the hinge member in the closed position;

Fig. 6 a cross-section of the hinge in the open position; and

Fig. 7 a view in perspective of a clip element employed in the hinge as will be hereinafter explained.

The numeral 1, Fig. 1, designates a casket having a front drop 2 which, as shown in Fig. 3, is lowered or opened to produce a couch effect when lined. The drop member 2 has heretofore been hinged to the casket side by the conventional form of piano hinge which consists of two long strips having coacting slotted portions that interact with a hinge pin, the length of the pin being coextensive with the length of the member which it is designed to secure. The piano form of hinge is expensive and when used on burial receptacles requires the removal of the paint or other coating to prevent spalling when the hinge is worked, which is a tedious and expensive operation. The present form of hinge obviates this difficulty and it is less expensive to manufacture while it retains the strength and desirable operating characteristics of the piano hinge.

In accordance with my invention, I utilize a

strip in the shape of the member 3, Fig. 5 of the drawing, which is provided with a bead 4 at its central portion and laterally extending hook-like wing elements 5, the strip 3 constituting the pivot member of the hinge. Hinge lugs 6 cooperate with the pivot strip 3, the lugs being attached to the members to be hinged designated by the numerals 7 and 8 and being curved as shown at 9 to constitute a sliding abutment for the elements 5 of the pivot strip. The ends of the lugs 6 are shaped complementary to the bead of the pivoted strip and terminate in a lateral flange 10. The ends of wall members 7 and 8 are chamfered to constitute fulcrum points when hinged as shown in Fig. 6. By chamfering the ends of members 7 and 8, any thickness or gage of metal can be hinged in this manner.

The hinge lugs 6 are oppositely spaced as shown in Fig. 4 and are secured to the members to be hinged by soldering, brazing or riveting, a soldered mount being designated by the numeral 11. The spacing of the lugs is in accordance with the strength of the joint required, Fig. 2 illustrating the spacing of the lugs a substantial distance apart which suffices for the application of the hinge burial receptacles which require a hinge that will resist a strain of about four hundred pounds, whereas the spacing in Fig. 4 is close and materially increases the strength of the joint.

The cooperative function of the pivot strip and hinge lugs together with the body of the members hinged is illustrated in Figs. 5 and 6 of the drawing, Fig. 5, showing what would be the closed position of the drop 2 in the casket, which is also shown in Fig. 2 of the drawing, wherein a latch 12 is provided to secure the drop in its closed position. In that position the lugs and hinge strip or bar are interlocked to prevent separation and displacement of the cooperating members. This interlocking position of the members is retained when the hinged parts are in their open position as shown in Fig. 6 as the edge of the members 7 and 8 abut against the hinge bar as shown and the hinge bar abuts against the hinge lugs as shown.

The resulting structure is simple in form, economical in its manufacture and application, and of durable mechanical quality. As shown in Fig. 1 of the drawing, the hinged member 2, when closed, completely obstructs the hinge structure excepting the bead 4 of the pivot strip which, however, not being subjected to movement, does not require removal of the surface finish as in the piano form of hinge, thus eliminating a tedious

and expensive scraping operation in casket construction.

To assemble the hinge parts, the pivot strip 3 is inserted with its bead portion in the space 5 between the members to be hinged. The lugs 6 are then placed in staggered relation as shown in Fig. 4 of the drawing, and the flat portion of lug 6 is then soldered to the metal surface of the members to be hinged designated by the numerals 10 7 and 8 in the drawing, the numeral 11 indicating the solder. Lugs 6 are preferably perforated at 6a to facilitate the spreading of the solder underneath the lugs.

When assembled, the pivot strip cannot be removed from between the lugs as the wall of the casket constitutes end abutments at 13 which prevents displacement of the pivot strip.

Although one embodiment of the invention has been herein illustrated and described, it will be 20 evident to those skilled in the art that various modifications may be made in the details of construction and in the arrangement of the cooperating parts without departing from the principles herein set forth.

25 I claim:

1. A hinge comprising a relatively wide pivot strip having a depressed central portion and laterally extending wing portions curved at their

ends, lugs cooperating with said strip having a curved portion complementary to the curvature of the lateral wing portions of the pivot strip and having a depressed portion complementary to the central depression of the pivot strip, said 5 pivot strip being disposed with its centrally disposed portion extending between the members to be hinged and said hinge lugs being fastened to the hinged member whereby the hinge strip, lugs and the edges of the hinged members coact 10 to form a slidably interlocked assembly.

2. A hinge comprising a pivot strip of thin gage flat material preshaped to form a channel having laterally extending portions, the ends of which are curved, hinge lugs adjacent the pivot strip 15 having tongues projecting into the channel portion of the strip and having a curved inner surface for engagement with the curved ends of the lateral portions of said pivot strip, alternate lugs being oppositely disposed and being secured to 20 the members to be hinged, and said hinge lugs having laterally extending end portions for abutting flat surfaces on said pivot strip, the members to be hinged abutting against a bead-like portion forming the channel of the pivot strip to constitute fulcrums for the pivot strip when the hinged members are subjected to pivot movement.

WALTER K. NELSON.
